GAME BOARD

Edmund F. Aldrich, R.D. 2, Newtown, Pa. 18940

Filed Oct. 20, 1969, Ser. No. 19,650

Term of patent 14 years

Int. Cl. D21—01

U.S. Cl. D34—5

The figure is a plan view of a game board showing my new design. The game board is of conventional thickness.

I claim:

The ornamental design for a game board, as shown and described.
